JAR

Bruce L. Roberts, Rossford, Ohio, assignor to Owens-Illinois Glass Company, Toledo, Ohio, a corporation of Ohio

Filed Dec. 6, 1960, Ser. No. 63,126

Term of patent 14 years

(Cl. D58—25)

The FIGURE is a side elevational view of a jar showing my new design.

The side not shown is substantially the same as that shown.

The characteristic features of my design reside in the two bulged areas directly under the neck and surrounding the jar, and the outwardly flared lower portion which curves inwardly to the bottom thereof.

I claim:

The ornamental design for a jar substantially as shown and described.
